~~FIG. 4.~~

UNITED STATES PATENT OFFICE.

SAMUEL KLEIN, OF CHICAGO, ILLINOIS.

BUILDING CONSTRUCTION.

Application filed February 4, 1927. Serial No. 165,917.

My invention relates to improvements in building construction, more particularly in the making of concrete flooring, and it consists in the combination, constructions, and arrangements herein described and claimed.

An object of my invention is to provide a floor which is light, shallow, and yet which has great relative strength.

A further object is to provide a construction in which the ceiling is level, with no projecting beams.

A further object is to provide a building construction in which there is a saving in the cost of materials, an economy in the use 15 of forms, and with considerably reduced dead loads.

A further object is to provide a building construction which will give greater stiffness against forces such as wind.

20 Other objects and advantages will appear in the following specification, and the novel features of the invention will be particularly pointed out in the appended claims.

My invention is illustrated in the accompanying drawings, forming part of this application, in which

Figure 1 is a plan view showing a floor in the course of construction,

Figure 2 is an enlarged section along the line 2—2 of Figure 1, with the addition of the cement filling covering the pans,

Figure 3 is a section at right angles to Figure 2 along the line 3—3 of Figure 2, and

Figure 4 is a perspective view of pans and metal soffit used in the building construction.

In the following description, I will make use of definite dimensions in specifying the arrangement of the various parts, but it will be understood that this is for sake of illustration only and that other dimensions than those given might be used without departing from the spirit and the scope of the invention.

In carrying out my invention, I make use 45 of a metal framework consisting of steel girders 5 which are preferably I or H beams. These girders may be spaced say eighteen feet apart in both directions. In Figure 1 I have shown a square made up of such 50 girders.

Between the girders, I place wood-form soffits 6. These are preferably 2 x 6 planks laid about 3' and 9" (centers) apart and they are shored up as by supports 7 of any 55 suitable nature. A form 8 may be used un-

derneath the girder 5 with a suitable support 7.

It will be noted that the wood soffits are laid in one direction only. Upon these soffits I place pans 9, such as that shown in Figure 4. These pans have preferably square tops and their sides are placed substantially three inches from the pans in the adjacent row and also the same distance from the adjacent pans in the same row. Between the pans of the same row, I make use of a metal soffit such as that shown at 10 in Figure 3. This is of U-shaped form and, as will be observed, is inverted with respect to the adjacent pans. The edges of the U-shaped soffit rest on the 70 wood soffit 6 and the soffits 10 form closures for the ends of adjacent pans 9.

In Figure 1 I have shown two rows of these pans. When they have been placed in position, reinforcing rods such as those shown at 11 are placed in the spaces between the rows of pans as well as in the metal soffits and then the cement 12 is poured and is left to harden. Now, when the supporting forms are removed, there will be a floor 80 section between the girders consisting of recesses where the pans were placed and concrete beams in the spaces between the pans as well as those formed by the metal soffits. These beams will form integral supporting 85 members running at right angles to each other.

It will be seen that in the use of this construction I have made a floor which is strong and yet light and comparatively shallow. 90 Furthermore, the use of the metal soffits obviates the necessity of wood-form soffits and the supporting of these soffits between those which are arranged longitudinally.

When the concrete forms have been removed, it will be observed that the under side of the concrete beams thus made are in the same horizontal plane, so that when the ceiling is finished, as by placing metal lath underneath the beams, and the latter is 100 plastered, the ceiling will be flat and will not have beams projecting down below it as in other forms of concrete construction.

I claim:

1. The herein described process of making 105 concrete flooring, which consists in providing a series of parallel rows of soffits, placing on said soffits rows of pans spaced equally apart from others in the row and from similar pans in adjacent rows, in clos- 110

ing the ends of the pans in any row by **U**-shaped soffits, in placing a layer of concrete over the pans and in the spaces therebetween, and subsequently removing the pans and soffits, whereby a floor having beams running at right angles to each other is formed.

2. A building construction comprising a series of soffits disposed in parallel relation,

said soffits being spaced apart, pans having open ends disposed upon the soffits and arranged in spaced relation, the ends of said pans being in parallel relation, and **U**-shaped soffits having smooth walls and disposed between the spaced-apart pans for closing the open ends of said pans.

SAMUEL KLEIN.
